FLOAT-CONTROLLED VALVE-OPERATING MECHANISM.

1,409,550.

Specification of Letters Patent. Patented Mar. 14, 1922.

Application filed July 12, 1920. Serial No. 395,585.

To all whom it may concern:

Be it known that I, IRVING C. JENNINGS, a citizen of the United States, and resident of South Norwalk, county of Fairfield, 5 State of Connecticut, have invented certain new and useful Improvements in Float-Controlled Valve-Operating Mechanisms, of which the following is a specification.

This invention relates to mechanism for 10 controlling the level of a liquid contained in a tank or receptacle, and particularly to mechanism of this class adapted to maintain a constant liquid level in a collecting tank by permitting the outflow of excess 15 liquid, although it may be utilized, if desired, to control the inflow of liquid into any receptacle from which liquid is withdrawn and in which it is desired to have a constant supply.

20 An object of the invention is to provide a simple, compact, and inexpensive float controlled mechanism which is so constructed that a float of relatively small size is enabled to operate a large sized valve or, to 25 operate a valve against high back pressure of fluid, as when the liquid pressure is supplemented by the pressure of a gas above it, within a closed receptacle. Another object is to provide such a mechanism which 30 may be assembled on a single base or supporting member enabling it to be removed as a unit for inspection purposes. Another object is to provide mechanism of this 35 class having no sliding parts, and no tightly fitting moving elements whereby all tendency of the valve to stick is avoided.

The invention will be fully disclosed in the following description when taken in connection with the accompanying drawings, 40 in which,

Figure 1 is a section through a tank and through the improved liquid level controlling mechanism, and

45 Figure 2 is a section on line 2-2 of Fig. 1.

The tank indicated at 10 in the drawings may be of any size and shape, and has a circular opening 11 near the bottom through which the casting 12 extends, this casting 50 being secured by bolts 13 to the wall of the tank in such manner as to make a water tight fit, but at the same time being readily removable. The casting has a hollow interior serving as an outlet passage for liquid

from the tank, the inlet opening of said 55 passage being indicated at 14 and the outlet opening at 15. Preferably a bushing is fitted into the inlet opening, and an annular valve seat 16 formed thereon.

A valve 17 is arranged to seat on said 60 valve seat 16 and this valve may have downwardly extending guide portions 18 which assist in maintaining the valve in proper alignment with the valve seat as it is moved in service and the liquid escaping from the 65 tank when the valve is raised passes between these guides.

Spaced lugs 19 extend laterally from the inner wall of member 12 and a bell crank lever B is pivotally supported between these 70 lugs, the pivotal axis of the bell crank lever being at right angles to the axis of the outlet opening and intersected thereby, or lying 75 very close to this axis. The bell crank lever may be made in various forms but preferably 80 comprises a relatively long arm 20 having the float 27 connected to its outer end and which has threaded engagement at its inner end with a hollow boss projecting at right angles from the wider but relatively short 85 arm 22. Links 23 connect the short arm 22 to the axle 24 secured to the valve and extending diametrically across the same. Arm 22 and links 23 constitute a toggle lever and the lengths of the arm and links are such 90 that they will each lie in a plane through the bell crank axis and the center of the valve, when the valve is seated, that is, the toggle will be straight.

For the purpose of preventing lateral displacement of the valve when raised high from its seat links 25 are provided, these 95 links being journaled on the axle 24 at their inner ends and pivotally secured to lugs 26 integral with the member 12, at their outer ends. The pivotal connections are loosely made so that the parts will not have a tendency to stick or jam in operation. Stops 27 on lugs 19 are provided to positively stop the movement of the bell crank lever as the 100 valve closes, and to prevent its being again raised, which might occur in case a slight leakage should permit the short arm 22 moving past its lowermost position.

In operation the valve will remain closed 105 until a sufficient amount of fluid has accumulated in the tank to raise the float. The opening of the valve is opposed by the pres-

sure of the liquid and by the pressure of any compressed gas which may be in the tank above the liquid, and a considerable force is necessary to effect the initial opening movement. At opening the lever arm of the float will be greatest and the lever arm of the resisting fluid pressure on the valve smallest, inasmuch as the arm 22 and links 23 are nearly in a straight line. A comparatively small float is therefore capable of opening a valve against high back pressure or of opening a large valve against low back pressure, by the arrangement of mechanism described. After the valve is once opened the float may rise quickly, as the pressure on the valve immediately drops off, to open the valve wide. As the float rises its effective lever arm of course is decreased while the effective length of the "work" arm is increased. This insures a rapid opening of the valve after its initial opening has been accomplished. The apparatus is small and compact and being mounted on a single base plate or member can be removed as a unit for inspection purposes.

It will be obvious that changes may be made in the design and arrangement of the parts of the invention which is therefore not limited to the exact form described and illustrated. The valve may be arranged, for instance, to regulate the flow of liquid into instead of out of, a tank or receptacle.

Having thus described my invention what I claim as new and desire to secure by Letters Patent is:

1. The combination with a liquid container having an outlet, of a valve for the outlet and valve operating means comprising a pivoted arm having a float connected thereto, and toggle levers connecting said arm and valve, one of said levers being rigidly connected to the arm and the other pivotally connected to the valve, said levers be-

ing so arranged as to be substantially in alignment when the valve is closed, for the purpose set forth. 45

2. The combination with a liquid container having an outlet, of a valve for the outlet and valve operating means comprising an arm having a float connected thereto and pivotally supported substantially in alignment with the axis of the opening, and toggle levers connecting said arm and valve, one of said levers being rigidly connected to the arm and the other pivotally connected to the valve, said levers being so arranged as to be substantially in alignment when the valve is closed, for the purpose set forth. 50 55

3. The combination with a liquid container having an outlet, of a valve for the outlet, a guide link pivotally supported at one end adjacent said outlet and pivotally connected at its other end to said valve, and valve operating means comprising a pivoted arm having a float connected thereto, and toggle levers connecting said arm and valve, said levers being so arranged as to be substantially in alignment when the valve is closed, for the purpose set forth. 60 65

4. The combination with a liquid container having a liquid outlet opening with vertically disposed axis, of a vertically movable valve for said outlet and valve operating means comprising an arm having a float connected thereto and pivotally supported substantially vertically above the center of the outlet opening, and toggle levers connecting said arm and valve, one of said levers being rigidly connected to the arm and the other pivotally connected to the valve, 70 75 80 said levers being so arranged as to be in substantially vertical alignment when the valve is closed, for the purpose set forth.

In testimony whereof I affix my signature.

IRVING C. JENNINGS.
